UNITED STATES PATENT OFFICE.

GIOVANNI EMANUELE ELIA, OF NEW YORK, N. Y.

TORPEDO-BOAT.

1,312,391.

Specification of Letters Patent.

Patented Aug. 5, 1919.

Application filed January 25, 1917. Serial No. 144,480.

To all whom it may concern:

Be it known that I, GIOVANNI E. ELIA, a subject of the King of Italy, residing in the city of New York, county of New York, and State of New York, have invented certain new and useful Improvements in Torpedo-Boats; and I do hereby declare the following to be a full, clear, and exact description of the invention, such as will enable others skilled in the art to which it appertains to make and use the same.

This invention relates to torpedo boats, and particularly to the means for discharging torpedoes therefrom.

An object of the invention resides in so constructing the boat and locating the torpedoes within the same that the liability of the latter prematurely exploding, even when the boat contacts with and causes the explosion of a submarine explosive, is reduced to the minimum.

A further object of the invention resides in so constructing the torpedo boat that the torpedoes will be discharged transversely to the line of movement of the boat, so that a ship may be attacked when the course of the torpedo boat is substantially parallel to the course of the attacked ship.

A further object of the invention resides in so constructing the torpedo discharging mechanism that a predetermined number of torpedoes may be successively discharged so as to form, in effect, a barrier to the ship which is being attacked.

With these and other objects in view, such as will appear as my description progresses, my invention comprises the combination and arrangement of parts as set forth in and falling within the scope of the appended claims.

In the drawings:

Figure 1 is a plan view of a torpedo boat constructed in accordance with my invention;

Fig. 2 is a side elevation thereof;

Fig. 3 is a diagrammatic view illustrating the barrier formed by the successively discharged torpedoes before the attacked ship has penetrated the barrier;

Fig. 4 is a similar view, but showing the ship after it has penetrated, and illustrating the manner in which the torpedoes will be located with respect to the ship;

Fig. 5 is an elevational view illustrating the several positions of a torpedo from its

discharge from one side of the boat until it reaches a position at a predetermined distance from the surface of the water;

Fig. 6 is a similar view, but showing the torpedo discharged from the opposite side of the ship;

Fig. 7 is a transverse sectional view through the torpedo boat illustrating the location of the protective means and the torpedo discharging means;

Fig. 8 is a longitudinal sectional view through a portion of the boat and the discharging tube; and

Fig. 9 is a detail.

In the drawings, I have illustrated my invention as embodied in a torpedo boat which is designated generally by the reference character A, which is propelled by suitable motive power (not shown). This boat consists of a hull B, to which entrance is gained through a hatchway C. The main hull is provided with an armor G, and below the same with a protective device D, which is constructed, preferably, in accordance with my invention as set forth in my co-pending application, Serial No. 136,037, filed December 9, 1916, and consists, broadly, of a shell F which envelopes the hull B below the water line and is provided with longitudinally extending cells E, which consist, preferably, of metal and wood, or such other materials that the combined densities will be equal substantially to that of the water of flotation, so that should a portion of the protective device be torn away by a submarine explosion, the equilibrium of the boat will not be destroyed as the water of flotation fills the blown-away or destroyed portion of the protective device.

In order that the torpedoes may be discharged successively from the bottom of the boat and transversely to the line of movement thereof, I have provided one or more discharge tubes 1, which extend from within the main hull B rearwardly and downwardly through the boat and open beneath the bottom thereof. Each of these tubes is rectangular in cross section and of sufficient width to accommodate the ordinary torpedo, such as illustrated in Figs. 7 and 8 of the drawings, and indicated by the reference character α . At the upper end of this tube 1, within the hull of the boat, is a door 2, which is provided with suitable pivoted locking bolts 3. This door extends com-

pletely across the discharge or torpedo tube 1, being of sufficient length to permit the placing of the torpedoes in the tube, so that their longitudinal axes extend exactly transversely of the tube. At the lower end of the tube a door 4 is provided, which normally closes the end, but is adapted to be operated to open the same by means of an operating chain 5 which extends into the hull B as illustrated in Fig. 8.

In order that the torpedoes may be positively forced from the tube 1, I have provided a follower 6 in the upper end of the tube, which follower is forced downwardly within the tube and against the torpedoes by means of compressed air, which enters between the head 7 of the tube and the follower 6 through the medium of a valved pipe 8, which extends from a suitable source of compressed air, such as the storage tank 6' illustrated in Figs. 7 and 8. The follower 6 is retracted and brought to its initial position between the door 2 and the head 7, so as to permit the placing of the torpedoes in the tube, by means of a winding drum 9 on which a suitable cable 10 operates, which cable extends through the head 7 and is attached to the follower 6. This drum 9 is operated by any suitable means, such as a motor 11. It will thus be seen that as the follower 6 is forced downwardly in the tube, and when the door 4 at the lower end thereof is open, the torpedoes will be forced from the tube, so that their longitudinal axes will extend in a transverse relation to the longitudinal axis of the torpedo boat. At the lower end of the tube 1, a suitable cam 12 is provided, which cam operates the trip levers 13 on the torpedoes as they move successively from the tube 1, which trip levers set in motion the propelling mechanisms of the torpedoes. It is to be understood that the torpedoes are of a construction which is commonly used, and a detailed description of the same is, therefore, not here indulged in.

In operation, when it is desired to discharge a series of torpedoes at an objective ship, or the like, it is only necessary to open the door 2 in the tube 1 and place the desired number of torpedoes in the tube, the communication between the tube and the air storage tank 6' being at this time cut off by the valve in the pipe 8. After the placing of the torpedoes within the tube, they assume such a position as is illustrated in Fig. 8 of the drawings, and upon the closing of the door 2 and the clamping of the same in place by the bolts 3, the valve in the pipe 8 may be opened to allow the air from the tank 6' to exert pressure against the follower 6. When the door 4 at the lower end of the tube is opened by means of the lifting chain 5 and the hand-wheel 65 for operating the same, the torpedoes will

be forced successively from the tube 1 by the follower 6, the cable 10 at this time paying out from the drum 9. It will be understood that the torpedoes do not move down the tube or passageway by gravity 70 but must be moved downwardly by the follower 6 and the air pressure exerted thereon. The discharging operation is therefore under the control of the operator in admitting compressed air to the tube 1 or discontinuing the admission of air thereto. Also, the torpedoes do not roll on the bottom wall of the tube but slide thereover. If necessary, special provision may be made to prevent rolling and therefore placing the 80 torpedoes in the tube in the proper position insures coaction of the starting lever of each torpedo with the cam at the lower end of the torpedo tube. As each torpedo passes from the tube, the propelling mechanism thereof 85 will be set in motion by the actuation of the trip lever 13 by the cam 12. The torpedoes will be discharged transversely to the course of the torpedo boat, as will be readily obvious upon an inspection of Fig. 7 of the 90 drawings, and, consequently, the boat may run parallel to the course of the objective ship during the discharge of the torpedoes.

In Figs. 5 and 6 of the drawings, I have illustrated the manner in which the torpedoes are discharged from the tube 1, illustrating in Fig. 5, the torpedoes passing from the starboard side of the torpedo boat, and in Fig. 6 the torpedoes passing from the port side of the boat. Of course, the determination of the side from which the torpedoes leave the torpedo boat depends upon the direction in which they are placed in the tube 1, as will be readily appreciated. As illustrated in Figs. 5 and 6 of the drawings, the torpedoes will, upon being discharged from beneath the torpedo boat, in their progress toward the objective ship, rise to the proper depth of submersion, so that the penetration of the objective ship 110 will take place at the proper distance below the water line.

In Figs. 3 and 4 of the drawings, I have illustrated the manner in which a series of torpedoes may be discharged from the boat 115 when the boat is running in advance of the objective ship. Fig. 3 discloses torpedoes as forming, in effect, a barrier which is the result of the successive discharging of the same, from the torpedo tube. Fig. 4 discloses the manner in which the objective ship, in attempting to penetrate the barrier, is struck by one of the torpedoes. It is, of course, to be understood that it is possible for more than one of the torpedoes to strike 125 the side of the objective ship, and this depends upon the advance of the ship after having been struck by one of the torpedoes and also upon the rapidity with which the torpedoes are discharged from the tube. 130

The several torpedoes in Figs. 3, 4 and 5 are designated by the characters *a* to *g*, inclusive.

It will, therefore, be seen that I have not only provided a novel means for discharging the torpedoes from the torpedo boat, but have also provided a novel method of discharging the torpedoes so that at least one will necessarily find its mark.

10. What I claim is:—

1. The combination, with a torpedo boat; of a torpedo discharging mechanism comprising a wide, shallow tube having its mouth disposed transversely of the boat, 15 means for forcing a torpedo broadside through said tube while holding it against rotation, and means for automatically setting the propelling mechanism in operation as the torpedo passes through said mouth.
20. 2. The combination with a torpedo boat, of means for automatically forcing torpedoes from the bottom of the boat with their axes extending transversely of the boat and at a rate which is under the control of the operator, and means for succe- 25

sively setting in motion the propelling mechanisms of the torpedoes as they are discharged.

3. The combination with a torpedo boat, of means for conveying a series of torpedoes to a position beneath the boat with their axes transversely thereof, and means for forcing the torpedoes successively from said conveying means at a rate which is under the control of the operator. 30 35

4. The combination with a torpedo boat, of a torpedo discharging mechanism including a torpedo tube extending through the bottom of the boat, a manually operable door at the lower end of the tube, a similar door at the upper end of the tube, a follower operable in the tube, means for conveying air under pressure between the follower and the upper closed end of the tube to cause the movement of the follower toward the open end of the tube, and means for retracting the follower. 40 45

In testimony whereof I affix my signature.

GIOVANNI EMANUELE ELIA.
